UNITED STATES PATENT OFFICE.

WILLIAM HENRY GUNTHER, OF OWENSBOROUGH, KENTUCKY.

STEAM-ENGINE GOVERNOR.

SPECIFICATION forming part of Letters Patent No. 602,578, dated April 19, 1898.

Application filed October 7, 1897. Serial No. 654,339. (No model.)

To all whom it may concern:

Be it known that I, WILLIAM HENRY GUN-
THER, of Owensborough, Daviess county, Ken-
tucky, have invented certain new and useful
5 Improvements in Steam-Engine Governors, of
which the following is a specification.

My invention relates to improvements in
centrifugal fly-ball governors, and the im-
provements will be readily understood from
10 the following description, taken in connection
with the accompanying drawings, in which—

Figure 1 is a rear elevation of a governor
exemplifying my improvements; Fig. 2, a vertical
15 section thereof in the plane of the axis
of the driving-shaft; Fig. 3, a side elevation
of the governor; Fig. 4, a side elevation
of the stop-motion cam and the stem-lip engaged
by it, and Fig. 5 a perspective view of the
20 stop-motion cam and stem-lip shown as sepa-
rated.

In the drawings, giving particular attention
to Fig. 2 and referring to the other figures
of the drawings incidentally, 1 indicates the
25 usual valve structure of throttling-govern-
ors; 2, the governor-housing, mounted, as
usual, thereon and comprising a bonnet for
the valve-chamber, an arch over the stuffing-
box, a bearing for the driving-shaft, and a
30 bearing for the vertical rotary parts; 3, the
usual stem attached to the governor-valve
and projecting upwardly into attachment
with the head of the governor, this stem, as
usual, closing the governor-valve by a down-
35 ward movement; 4, the foot of the governor,
the same consisting of a journal rotating in
a bearing in the top of the housing concentric
with the valve-stem 3, a block being formed
upon the upper portion of this journal; 5, a
40 collar fitting loosely within a circumferential
groove in the journal of foot 4; 6, a set-screw
in the bearing engaged by the journal of the
foot of the governor, this set-screw holding
collar 5 against rotation and end movement,
45 whereby the foot-journal of the governor is
restrained against vertical motion in its bearing
in the housing; 7, the usual bevel-gear fast
on the foot of the governor; 8, the usual
driving-shaft journaled in the horizontal
50 bearing of the housing, its axial line inter-
secting the axial line of the foot-journal of
the governor; 9, a bevel-gear fast on the driv-
ing-shaft and engaging bevel-gear 7, as usual,

the hub of this bevel-gear abutting, as usual,
against the inner end of the journal of the
driving-shaft; 10, the inner end of the driv- 55
ing-shaft, the same having a bearing engage-
ment with the exterior of the housing-bearing
in which runs the foot-journal of the gov-
ernor; 11, the driving-pulley, fast upon but
adjustable along the driving-shaft; 12, a sta- 60
tionary journal-tube disposed axially with
reference to the foot-journal of the governor,
the lower end of this tube being fast and rigid
in the housing, the foot-journal 4 of the gov- 65
ernor surrounding this tube and taking a
bearing thereon, the foot-journal having a
long upward extension fitting around the
journal-tube, so that the foot-journal 4 not
only has a bearing within the housing, but 70
has an extended bearing around the journal-
tube, the valve-stem 3 passing freely through
the journal-tube; 13, the head of the gov-
ernor, the same comprising a tubular bearing
surrounding the upper portion of the journal- 75
tube, so as to turn and move vertically there-
on, and a block at its upper portion; 14, thin
flat suspender-springs having their upper
ends rigidly secured to the block of the head
of the governor; 15, the governor-balls, firmly 80
secured to the lower ends of the suspender-
springs 14; 16, yokes straddling the governor-
balls and articulated thereto by horizontal piv-
ots and projecting downwardly from the balls;
17, thin flat springs having their upper ends 85
firmly secured to the yokes 16 and having their
lower ends firmly secured to the block of the
governor-foot, the yokes forming, in effect,
upper terminals of the springs 17, articulated
to the balls; 18, adjusting lock-nuts on the 90
upper end of valve-stem 3; 19, a cap-nut 90
screwed upon a threaded boss on the gov-
ernor-head, this cap-nut having a counter-
bore engaging above lock-nuts 18 or, prefer-
ably, over washers disposed on the valve-stem 95
over the lock-nuts; 20, a helical spring sur-
rounding valve-stem 3, its lower end resting
on the upper end of journal-tube 12, its up-
per end abutting under the lock-nuts 18, this
spring having sufficient strength to lift the 100
valve-stem and valve and overcome the fric-
tion of the valve-stem in its stuffing-box, the
tendency of the spring thus being to hold the
valve-stem in as high a position as the head
of the governor will permit, the valve-stem

thus rising and falling with the head of the governor; 21, a tubular nut threaded around the tubular bearing of governor-head 13, its lower end presenting itself toward the governor-foot and its upper end being provided with a capstan-head; 22, the centripetal spring of the governor, the same being a helical spring surrounding the upper tubular bearing of the governor-foot, the lower end 10 of the spring resting on a shoulder on the governor-foot, the upper end of the spring abutting against the lower end of nut 21; 23, a sleeve having its lower end carried by the governor-foot, the sleeve surrounding the 15 spring 22 and its upper end surrounding the lower portion of nut 21; 24, a lip-piece fast on the governor-stem below the arch of the housing; 25, a lip projecting horizontally therefrom toward the pulley side of the governor; 20 26, a cam-shaft journaled in the housing below and parallel with the driving-shaft, the inner end of this cam-shaft projecting over the lip 25; 27, a plate-cam fast on the inner 25 end of the cam-shaft and over the lip 25, this cam consisting of two side lobes and an intermediate depression engaging over the lip 25; 28, stops projecting inwardly from cam 27 and adapted, as the cam is turned in either direction, to come in contact with lip-piece 30 24 and limit the angular motion of the cam; 29, a hub adjustably secured to the outer end of the cam-shaft; 30, an arm projecting outwardly from this hub; 31, a pulley carried by the outer end of arm 30 and adapted to rest 35 upon the belt which drives the governor; 32, attachment devices upon lever 30, adapted to receive connection from cord, chain, lever, or other devices employed when the governor is to be used as a sawyer's valve, and 33 the 40 governor-belt.

Under the action of centrifugal force the balls fly out, springs 14 and 17 flexing to permit the motion, the lower springs 17, however, having an articulate motion with reference to the balls, by reason of the presence 45 of the pivots uniting the yokes to the balls. As the balls move outwardly the governor-head 13 moves downwardly and pressing down the valve-stem and closing the valve. 50 As the governor-balls move inwardly the spring 20 raises the valve-stem, so that the valve-stem accompanies the governor-head in its vertical movements. Spring 20 is comparatively light and is not intended to furnish the centripetal force for the governor. The descent of the governor-head as the balls move outwardly is resisted by spring 22, which spring furnishes the centripetal force 55 of the governor. The tension of this spring 60 may be adjusted by turning nut 21. Sleeve 23 completely incases the centripetal spring. The centripetal spring turns with the governor, and as its tension is increased by screwing downward upon nut 21 there is no increase 65 in friction of movement of the governor parts. Nuts 21 permits of a very extended adjusting movement, thus providing

for delicate adjustments for the speed of the governor. Driving-pulley 11 is, as usual, adjustable along the driving-shaft, and its hub 70 may or may not engage against the outer end of the bearing of the driving-shaft; but inward motion of the driving-shaft is prevented by its end bearing 10. Pulley 31 rests on the governor-belt, and 75 arm 27 is thus maintained in normal idle position, in which position it is without effect upon the valve-stem. If the belt breaks or runs off its pulleys, then pulley 31 drops, thus turning the cam, which results in moving the 80 valve-stem downwardly and closing the valve. This forms the safety-stop of the governor. When the cam moves the valve-stem downwardly, the light spring 20 yields and permits of the movement, it thus not being necessary 85 that the safety-stop should overcome the resistance of the comparatively stiff centripetal spring. Cam 27 has two lobes, and arm 30 may be adjusted to project either to the front or rear, thus providing for a driving-belt leading to the governor in either direction. When the governor is to be used as a sawyer's valve, then the usual hand controlling devices may be connected with lever 30 at attaching-point 32, lever 30 thus becoming 90 the sawyer's valve-lever, and when the governor is thus used the comparatively light spring 20 permits the proper movements of the valve-stem without disturbing the vertical position of the governor-head or disturbing 95 the centripetal spring.

I claim as my invention—

1. In a governor, the combination, substantially as set forth, with a governor-head and governor-foot mounted for rotation, of thin flat springs firmly secured to the governor-head and depending therefrom, a ball firmly secured at the lower end of each of said springs, and thin flat springs having their lower ends secured to the governor-foot and having their upper ends articulately connected with said balls through the medium of horizontal pivots.

2. In a governor, the combination, substantially as set forth, with a governor-head and governor-foot mounted for rotation, of thin flat springs firmly secured to the governor-head and depending therefrom, a ball firmly secured at the lower end of each of said springs, bifurcated yokes depending from said balls and articulated thereto by horizontal pivots, and thin flat springs having their upper ends firmly secured to said yoke and having their lower ends firmly secured to the governor-foot.

3. In a governor, the combination, substantially as set forth, of a housing having a vertical bearing in its top, a journal-tube concentrically disposed within said bearing and projecting above the same and having its foot 125 firmly secured in the housing at the base of said bearing, a governor-foot mounted for rotation on said tube and having a journal fitting within said bearing and provided with a

circumferential groove, a collar engaging said groove, a set-screw in the wall of said bearing and serving to hold said collar rigid in the bearing, a governor-head mounted to turn 5 and move vertically upon the upper portion of said journal-tube, governor-balls connected with said governor-foot and governor-head, a spring to resist the outward movement of the balls, a valve-stem connected with the governor-head, and means for transmitting rotary motion to the governor foot and head and balls.

4. In a governor, the combination, substantially as set forth, of a housing, a journal-tube 15 firmly supported thereby, a governor-foot mounted for rotation on said journal-tube, a governor-head mounted for rotation and for vertical movement on said journal-tube, governor-balls connected with the governor-head 20 and governor-foot, a part surrounding said journal-tube and projecting from the governor-head toward the governor-foot, a helical spring surrounding the journal-tube and compressed between the foot of said last-mentioned part and a shoulder on the governor-foot, and a tube surrounding said spring and having its foot secured to the governor-foot and having its upper end surrounding the upper abutment of the spring.

30 5. In a governor, the combination, substantially as set forth, of a housing having a vertical bearing and a horizontal bearing with their axes intersecting, a journal-tube firmly supported by the housing concentric with 35 said vertical bearing and projecting upwardly therefrom, a governor-foot mounted for rotation in said vertical bearing, a governor-head mounted for rotation and for vertical movement on said journal-tube, balls connected 40 with the governor-head and governor-foot, a bevel-gear upon the governor-foot, a driving-shaft mounted in said horizontal bearing and having its inner end in bearing engagement within the exterior of said vertical bearing, 45 and a bevel-gear upon the inner end of said driving-shaft with its hub abutting against the inner end of said horizontal bearing.

6. In a governor, the combination, substantially as set forth, of a governor-head arranged 50 for rotation and for vertical movement, a valve-stem engaging upwardly against a surface on the governor-head and free to move downwardly with reference to the governor-head, a spring serving to support the valve- 55 stem in an upward position against the shoulder on the governor-head, centrifugal devices serving to move the governor-head downwardly, a centripetal device serving to move the governor-head upwardly, and mechanism 60 for forcibly lowering the valve-stem against the resistance of the first-mentioned spring

without disturbing the second spring or the governor-head.

7. In a governor, the combination, substantially as set forth, of a housing, a journal-tube 65 supported thereby, a governor-foot mounted for rotation on the journal-tube, a governor-head mounted for rotation and for vertical movement on the journal-tube, balls connected with the governor-foot and governor-head, a valve-stem within the journal-tube and projecting above the same, upwardly and downwardly presenting shoulders at the top of the valve-stem, a cap-nut upon the governor-head engaging the upwardly-presenting 70 shoulder of the valve-stem, a spring compressed between the downwardly-presenting shoulder of the valve-stem and the upper end of the journal-tube, and mechanism for lowering the valve-stem with reference to the 75 governor-head and against the resistance of said spring.

8. In a governor, the combination, substantially as set forth, of a housing, a journal-tube carried thereby, a governor-foot mounted for 85 rotation on the journal-tube, a governor-head mounted for rotation and for vertical movement on the journal-tube, balls connected with the governor-foot and governor-head, a valve-stem engaging upwardly against a part 90 of the governor-head so as to be forced downwardly as the governor-head moves downwardly, a spring supporting the valve-stem and yieldingly resisting its downward movement, a lip carried by the valve-stem, a cam-shaft mounted in the housing and having a cam 95 engaging said lip, and devices for partially rotating said cam-shaft.

9. In a governor, the combination, substantially as set forth, of a valve-stem connected 100 with the governing parts, a lip carried by the valve-stem, a cam-shaft mounted at right angles to the valve-stem and presenting its end over said lip, a double-lobed cam on said cam-shaft and engaging said lip, and an arm on 105 said cam-shaft to serve in giving the cam-shaft a motion of partial rotation.

10. In a governor, the combination, substantially as set forth, of a housing supporting the governing parts and the driving-shaft, a lip 110 carried by the valve-stem, a cam-shaft mounted in the housing parallel with the driving-shaft and presenting its end over said lip, a cam on said cam-shaft and engaging said lip, an arm projecting from said cam-shaft, and 115 a pulley carried by said arm and adapted to rest upon the governor-belt.

WILLIAM HENRY GUNTHER.
